UNITED STATES PATENT OFFICE.

MARTIN S. OLSON, OF MARMARTH, NORTH DAKOTA.

COAT-HANGER ATTACHMENT.

Application filed March 20, 1925. Serial No. 16,990.

To all whom it may concern:

Be it known that I, MARTIN S. OLSON, a citizen of the United States, residing at Marmarth, in the county of Slope and State 5 of North Dakota, have invented certain new and useful Improvements in a Coat-Hanger Attachment, of which the following is a specification.

This invention relates to improvements in garment hangers and is more particularly adapted to an attachment for a coat hanger, the purpose of which is to provide a means for retaining the shape of the coat while the same is supported on the hanger.

One of the important objects of the present invention is to provide a coat hanger attachment of the above mentioned character, which will in no way interfere with the supporting of the garment on the hanger, 20 the attachment providing a means for retaining the shape of the lapels of the coat.

A further object is to provide a coat hanger attachment of the above mentioned character which includes a means for adjusting the several parts comprising the same in order to accommodate various sizes 25 of coats.

A further object is to provide a coat hanger attachment of the above mentioned 30 character, which is simple in construction, inexpensive, and furthermore adapted for the purposes for which the same is designated.

Other objects and advantages of this invention will become apparent during the course of the following description.

In the accompanying drawing forming a 35 part of this specification and in which like numerals designate like parts throughout the same:

Figure 1 is a side elevation of the attachment embodying my invention showing a manner in which the same is associated with a coat hanger.

Fig. 2 is a sectional view taken approximately on line 2-2, Fig. 1, and

Fig. 3 is a fragmentary detail of the lower portion of the attachment.

In the drawing wherein for the purpose 50 of illustration is shown the preferred embodiment of my invention, the numeral 1 designates a coat hanger of the usual construction on which is adapted to be supported the coat and other garment.

My improved attachment comprises an upper and a lower bar of flat metal, the

same being designated by the numerals 2 and 3 respectively. The adjacent ends of said bars are hingedly connected together as illustrated at 4. The upper bar 2 is twisted intermediate its ends as illustrated at 5, the upper end of the upper bar being secured to the central portion of the coat hanger 1 on one side thereof as illustrated at 6. The twisted portion 5 is disposed at 65 substantially right angles to the upper bar 2 and provides a finger engaging portion.

The purpose of the twisted portion 5 is to provide a means for holding the coat hanger while placing a coat thereon. The lower 70 portion of the upper bar is disposed downwardly adjacent the horizontal cross bar or rod 7 associated with the coat hanger 1 in the usual manner for the purposes of supporting a pair of trousers.

An additional vertical bar 8 is adapted for vertical slidable movement on the lower bar and any suitable means such as is shown at 9 is provided for adjustably securing and supporting the slidable bar 8 on the lower bar 3. Lateral extensions 10 and 11 are formed on the lower end of the slidable bar 8 at the respective sides thereof. A pair of relatively short bars 12 and 13 are adjustably supported on the lateral extensions 10 and 11 respectively. A button 14 is attached to the bar 12 on the outer face thereof and the same is adapted to engage the upper button hole of the coat supported on the coat hanger. The opposite relatively short bar 13 is provided with a bayonet slot 15 for detachable engagement with the uppermost button on the coat which is ordinarily adapted for cooperation with the adjacent button hole on the opposite side of the front of the coat.

The lapels of the coat will overlap and the short bars will be disposed between the overlapping lapels as is clearly illustrated in Fig. 1.

The hinge 4 permits the lower bar 3 and the slidable bar 8 to be swung upwardly so as to permit the coat to be placed on the coat hanger in the usual manner. When the parts are arranged as shown in Fig. 1 of the drawing the coat and more particularly the lapels thereof will be maintained in proper shape while the garment is on the coat hanger. The attachment may be readily adjusted to accommodate various sizes of coats and also the adjustment of the short bars enables the same to be readily

placed in condition for cooperation with the button hole and button of the coat.

While I have shown the preferred embodiment of my invention, it is to be understood that various changes in the size, shape and arrangement of parts may be resorted to without departing from the spirit of the invention and the scope of the appended claims.

Having thus described my invention, what I claim as new is:—

1. A coat hanger attachment including a supporting bar secured at its upper end on said coat hanger, a relatively long bar adjustably associated with the lower portion of the aforementioned bar, lateral extensions formed on the respective sides of the lower portion of said last mentioned bar, and means carried by said lateral extensions for engagement with the uppermost button hole and button of a coat supported on the coat hanger.

2. A coat hanger attachment including a supporting bar secured at its upper end on said coat hanger, a relatively long bar adjustably associated with the lower portion of the aforementioned bar, lateral extensions formed on the respective sides of the lower portion of said last mentioned bar, means carried by said lateral extensions for engagement with the uppermost button hole and button of a coat supported on the coat hanger, said last mentioned means comprising a pair of relatively short bars adjustably supported on said lateral extensions, one of said short bars being provided with a button for engagement with the uppermost

button hole on the front of the coat, the other relatively short bar being provided with a slot for detachable engagement with the uppermost button on the coat.

3. A coat hanger attachment including a supporting bar secured at its upper end on said coat hanger, a relatively long bar adjustably associated with the lower portion of the aforementioned bar, lateral extensions formed on the respective sides of the lower portion of said last mentioned bar, means carried by said lateral extensions for engagement with the uppermost button hole and button of a coat supported on the coat hanger, the upper portion of said supporting bar being twisted to provide a finger gripping portion.

4. A coat hanger attachment comprising a pair of flat bars the same being hingedly secured together at their adjacent ends, the upper bar secured at its upper end to the coat hanger, the intermediate portion of said upper bar being twisted to provide a finger gripping portion, a relatively long bar adjustably associated with the lowermost of said hingedly connected bars, lateral extensions formed on the lower end of said adjustable bar, and relatively short bars adjustably associated with said lateral extensions, said relatively short bars being provided with a button and slot respectively for detachable engagement with the uppermost button hole and button respectively of a coat supported on the coat hanger.

In testimony whereof I affix my signature.

MARTIN S. OLSON.
